UNITED STATES PATENT OFFICE.

BENJAMIN F. PERRY, OF PITTSBURGH, PENNSYLVANIA.

COLLECTION-BOX.

1,360,677.

Specification of Letters Patent. Patented Nov. 30, 1920.

Application filed September 10, 1919. Serial No. 322,840.

To all whom it may concern:

Be it known that I, BENJAMIN F. PERRY, a citizen of the United States, residing at Pittsburgh, in the county of Allegheny and State of Pennsylvania, have invented certain new and useful Improvements in Collection-Boxes, of which the following is a specification.

My invention consists of an improvement in collection boxes or similar devices, and has for its object to provide means for sounding an alarm upon the tampering therewith. While the invention, as illustrated and hereinafter described, refers to a form of collection boxes used for collecting and containing money offerings, as in connection with a church or other body, it will be understood that it is not essentially or particularly confined thereto, and may be utilized in any similar device.

The objects in view are to provide within a receiving receptacle of suitable shape and dimensions and provided with an opening door, a receiving drawer or box and an inlet conduit; means for ringing a bell or the like upon any unauthorized attempt to open the door or to remove the contents of the drawer or holder, by the closing of a circuit and the sounding of an electro-magnetic alarm or similar device.

In the drawings illustrating one preferred embodiment of the invention,

Figure 1 is a vertical sectional view through the middle portion of the box in normal operative position;

Fig. 2 is a similar view showing the closing gate of the conduit lifted by means of an extracting device and a resulting closing of the circuit;

Fig. 3 is a horizontal sectional view on the line III—III of Fig. 1; and

Fig. 4 is a partial vertical sectional view on the line IV—IV of Fig. 1.

The collection box or receptacle, in the form shown, is provided with side walls 2, a top 3, a bottom 4, and a door 5 hinged at 6 and covering an opening in one of the side walls. Said door is ordinarily closed and locked in any suitable manner and provides the only means of access to the interior of the box for the purpose of removing the receiving drawer 7 or its contents. For the purpose of providing means for closing an electric circuit upon the insertion of a knife blade, screw driver, or prying device of any kind, the free edge of the door 5

is provided with a strip of any suitable contacting material 8, as copper, throughout the length of its swinging edge, and the coacting edge of the frame at the side of the door opening is similarly provided with a strip 9. These strips are so located as to leave an intervening space sufficiently wide for the insertion of any instrument which might be used to pry or force open the door, the entry of which will thereby effect an electric closure between the two strips.

At any suitable position within the box, or elsewhere as preferred, is mounted an electric bell or alarm 10 having the usual attaching terminals for the circuit wires 11 and 12, the other terminals of which are connected with the strips 8 and 9 respectively, as clearly indicated in Fig. 1, one of such lead wires passing through the battery 13. The result of the closing of the circuit in the manner described is to cause a sounding of the alarm bell 10, whereupon the intruder is induced to discontinue further efforts to break into the box.

Below the inlet opening 14 for the introduction of money, a conduit 15 extends down to a point slightly above the receiving drawer 7, and such conduit is purposely deflected or shaped in the zig zag form as indicated, so as to prevent the easy introduction of any extracting instrument, as a stick, wire, or other article. It will not, however, prevent the introduction of such a device as a button, washer, or other weighted small article which may be attached to a flexible string or cord and provided with any adhesive material for the purpose of effecting the withdrawal of coins or paper money thereby.

For the purpose of preventing such removal, and also of sounding the alarm 10 upon such an attempt, the outlet terminal of conduit 15 is provided with a closing gate or fender 16 hinged or pivoted at 17 to the conduit and normally held open for free passage of coins, etc., by a retracting spring 18. The front edge of gate 16 is provided with a series of projecting pins or fingers 19 arranged somewhat closely together as shown in Fig. 4, extending slantingly downward and so arranged across the lower edge of the gate as to practically cover the discharge opening of the conduit 15.

One of the terminals 12^a of the circuit is connected with the contact plate 20 arranged in the path of movement of a similar contact

plate 21 of door 16, and connected with the other terminal 11^a of the circuit, as clearly shown in Fig. 1. In the event of a removing device *a* and cord *b* being lowered downwardly through the conduit into the money drawer 7, the device *b* will fall beyond the terminals of pins 19 and the supporting cord will then lie between two adjacent pins, so that when the cord is raised to remove an adhering coin, the device will become engaged against the under sides of the pins 19. Further upward tension will cause a closing of the door with a resulting closing of the contact terminals 20 and 21, as in Fig. 2, effecting a resulting sounding of the alarm 10.

With either means, *i. e.*, upon an attempt being made to open the door 5 or to remove the contents of the drawer 7 upwardly through the conduit 15, the alarm will sound, in which event the fraudulent attempt to rob the box will be ordinarily discontinued.

The device is comparatively simple in construction and efficient in operation in the manner intended. It may be changed or varied in detail construction, proportions, design or otherwise by the skilled mechanic, but all such changes are to be considered as within the scope of the following claims.

What I claim is:—

1. A collection box provided with a door 30 casing and an electrically actuated alarm device, an opening door in the casing having a conducting strip arranged along one edge thereof and in circuit with the alarm device, and a co-acting strip also in circuit with 35 the alarm device and mounted on the door casing in spaced juxtaposition to the door strip, whereby the door strip, and casing strip may be electrically connected by insertion of a conducting instrument.

2. A collection box provided with an interior alarm device, a hinged door having its swinging edge spaced away from the adjacent edge of the door opening, a conducting strip on the door edge and on the door 45 opening edge of the box respectively and normally spaced apart from each other when the door is closed, and means connecting each of said strips with the alarm device whereby to close the circuit thereto upon the 50 insertion of a conducting element between the strips.

In testimony whereof I hereunto affix my signature.

BENJAMIN F. PERRY
